CLAIM

The ornamental design for a cap closure, as shown and described.

DESCRIPTION

FIG. 1 is a front top perspective view of a cap closure, showing our new design;

FIG. 2 is a left side elevational view thereof;

FIG. 3 is a front elevational view thereof, the rear elevational view being a mirror image thereof;

FIG. 4 is a top plan view thereof;

FIG. 5 is a front top perspective view thereof, showing the cap closure in a closed configuration;

FIG. 6 is a right side elevational view of the closure of FIG. 1; and,

FIG. 7 is a right side elevational view thereof, showing the cap closure in a closed configuration.

The broken line showing of a tapered spout and a container tube is for illustrative purposes only and forms no part of the claimed design.
